US00D559861S

(12) **United States Design Patent** (10) **Patent No.:** **US D559,861 S**
(45) **Date of Patent:** **** Jan. 15, 2008**

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/265,581**

(22) Filed: **Sep. 1, 2006**

(51) LOC (8) Cl. **14-03**

(52) U.S. Cl. **D14/496**

(58) Field of Classification Search .... **D14/496, D14/401, 435, 474, 483, 217, 137, 138, 160, D14/168; 345/156, 169, 173-179, 905; 715/727-729, 715/864; 455/11.1, 7, 73, 344-347, 93, 95; 370/342-344; 369/1, 2, 6, 12; 463/43-47; 273/148 B**

See application file for complete search history.

(57) **CLAIM**

We claim the ornamental design for a media device, substantially as shown and described.

DESCRIPTION

FIG. 1 is a perspective view of a media device in accordance with the present design.

FIG. 2 is a front view for the media device.

FIG. 3 is a rear view for the media device.

FIG. 4 is a top view for the media device.

FIG. 5 is a bottom view for the media device.

FIG. 6 is a left view of the for the media device; and,

FIG. 7 is a right side view for the media device.

The features shown in broken lines in the various Figures are for illustrating environmental structure and form no part of the claimed design.

1 Claim, 2 Drawing Sheets
